CLAIM

The ornamental design for a holster for removably retaining medical shears, as shown and described.

DESCRIPTION

FIG. 1 is a front perspective view of a holster for removably retaining medical shears showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of parts of the drawings is included for the purpose of illustrating use and environment and forms no part of the claimed design.

1 Claim, 5 Drawing Sheets(56)
